(57) CLAIM

The ornamental design for an extended floating drive-on boat dock, as shown and described.

DESCRIPTION

FIG. 1 is a perspective view of a extended floating drive-on boat dock of the present invention;

FIG. 2 is a top plan view of the extended floating drive-on boat dock;

FIG. 3 is a bottom plan view of the extended floating drive-on boat dock;

FIG. 4 is a front elevational view of the extended floating drive-on boat dock;

FIG. 5 is a rear elevational view of the extended floating drive-on boat dock; and,

FIG. 6 is a side elevational view of the extended floating drive-on boat dock, the right and left sides being mirror images of each other.
